CURTAIN SUPPORT

Filed Feb. 13, 1930

UNITED STATES PATENT OFFICE

SIMEON L. SAWYER, OF CHICAGO, ILLINOIS, ASSIGNOR TO FRANK A. PETERS, OF CHICAGO, ILLINOIS

CURTAIN SUPPORT

Application filed February 13, 1930. Serial No. 428,006.

This invention relates to an improved curtain support, and more particularly to a rotatable support for window curtains and draperies or window curtains and valances 5 whereby the rods supporting the curtains and draperies may be swung outwardly away from the window frame and then lowered a desired distance to facilitate removal of the curtains and draperies from the supporting 10 rods or mounting of the same in place as the case may be. The curtain support also affords a convenient arrangement whereby the curtains and draperies of a window may be swung outwardly away from the window 15 without removal from the supporting rods to permit convenient access to be had to the panes of glass when it is desired to clean the same.

It is an object of this invention to provide 20 an improved curtain support which is adapted to be pivotally swung away from a window casing on which it is mounted and lowered a desired distance to facilitate the removal and replacement of curtains and 25 drapes from the support without recourse to the use of stepladders or similar devices.

It is also an object of this invention to provide an improved curtain support wherein the supporting brackets for the device com- 30 prises a plurality of interfitting sections adapted to be rigidly secured to a window frame with one of said sections adapted to be provided in any desired length depending upon the height of the window frame.

It is a further object of this invention to provide an improved curtain support of the type wherein the curtain supporting members are adapted to be swung outwardly away 40 from the window frame and then lowered smoothly and evenly without the customary chattering or vibrating movements which are eliminated by the use of improved bracing means for the stationary bracket member and by the provision of suitable gaskets through 45 which the slideable and rotatable member of the curtain support is required to slide during the raising and lowering of the members which support the curtains and drapes.

It is furthermore an object of this invention to provide an improved combination cur-

tain and drapery support of the type which is adapted to be swung toward and away from a window frame to facilitate mounting of curtains and draperies or the replacement of the same, said curtain support consisting of a 55 curtain supporting rod of U-shaped form and adjustable and having openings in the arms thereof to removably receive an auxiliary curtain or drapery supporting rod having a spring impelled gudgeon adapted to be removably sprung into place after curtains have been engaged thereon.

Still another object of the invention is to provide an improved curtain support of a type wherein the rods which support the curtains and draperies are supported on a slideable and rotatable rod having latching means for holding the supporting rods in a predetermined position with respect to the window frame but permitting elevation of the curtain 65 and drapery rods out of engagement with a supporting bracket to permit the curtain and drapery rods to be swung outwardly away from the window frame previous to the lowering of said rods to facilitate removal or 70 replacement of curtains and draperies from the rods.

It is an important object of this invention to provide an improved combination curtain and drapery support of the type wherein the curtain and drapery supporting members are adapted to be slightly lifted and then swung outwardly away from the window frame previous to the lowering of said supporting members by the slideable adjustment of a supporting rod which has sliding engagement through a stationary bracket carrying suitable gaskets to facilitate a smooth operation of the supporting rod with respect to the stationary bracket and with respect to an auxiliary guide bracket provided with suitable brace members to eliminate chattering or jerky movements with the lowering of the rods.

Other and further important objects of this invention will be apparent from the disclosures in the specification and the accompanying drawings.

This invention (in a preferred form) is 100

illustrated in the drawings and hereinafter more fully described.

On the drawings:

5 Figure 1 is a front inside elevation of a window casing or frame having mounted thereon an improved curtain support embodying the principles of this invention and illustrating the operation of the curtain support in dotted lines.

10 Figure 2 is an enlarged fragmentary vertical sectional view taken on line II—II of Figure 1 with parts shown in elevation.

15 Figure 3 is an enlarged fragmentary horizontal sectional view of the device taken on line III—III of Figure 1 with parts shown in elevation.

Figure 4 is an enlarged detail sectional view taken on line IV—IV of Figure 2.

20 Figure 5 is a horizontal detail view taken on line V—V of Figure 2.

As shown on the drawings:

25 The improved device consists of a combination curtain and drapery support adapted to be mounted upon a window frame 1 with the curtain and drapery supporting members extending horizontally across the top of the window frame and supported by means of a rotatable and slidable rod positioned at one side of the frame and supported in stationary 30 brackets secured to the frame upright.

35 The improved curtain support comprises a base or main bracket consisting of a mounting plate 2 having apertures therein to receive screws 3 whereby the bracket may be rigidly secured in a vertical position upon one side of the window frame or casing 1. Integrally formed on the lower end of the bracket plate 2 is an outwardly directed or projecting lower arm or flange 4 the outer 40 end of which is rounded and is provided with a slot 5, the inner end of which communicates with an opening in the flange arm 4. Integrally formed on the upper end of the bracket mounting plate 2 and projecting outwardly at right angles thereto is an upper arm or flange 6 provided with an opening directly above the opening in the arm 4. Secured or seated in the opening in the upper arm or flange 6 is a flanged gasket 7 constructed of fiber or other suitable material.

45 The upper arm 6 of the main bracket is also provided with a transverse opening or slot at 8 for the removable reception of the lower reduced end of an upper or auxiliary 50 guide bracket 9 the upper end of which is deflected at 10 to afford a foot 11 which is adapted to seat against the window casing and is provided with an opening for the reception of a retaining screw 12 or other suitable means for holding the auxiliary or upper bracket secured in place. The guide bracket 9 is provided with openings at spaced intervals through which screws 13 project. The screws 13 also project through spacer 55 sleeves or tubes 14 and are threaded into the

window casing 1 to hold the intermediate portion of the guide bracket 9 properly braced and reinforced in parallel relation to the window frame or casing as clearly illustrated in Figure 2. By this novel arrangement of providing two interfitting supporting brackets for the curtain support the upper guide bracket may be provided in any desired length depending upon the height of the window casing on which the improved device is to be mounted.

55 Slidably mounted upon the upper guide bracket 9 is a pair of parallel plates 15 the inner ends of which are provided with notches 16 to permit the same to be slidably engaged on the guide bracket 9. The two plates 15 are rigidly connected in parallel relation by means of a guide cylinder or sleeve 17 through which a reinforcing rod 18 slidably projects.

60 The lower end of the reinforcing rod 18 extends below the guide arm plates 15 and projects into the upper end of a tubular standard or hollow rod 19. The upper end of the tubular standard is secured to the lower portion of the reinforcing rod 18 by means of a set screw 20 or other suitable means.

65 The lower portion of the tubular standard 19 projects slidably through the fibre gasket 7 and through the opening in the lower bracket arm 4. A plug 21 is secured in the lower end 70 of the standard 19 and has a tongue 22 projecting downwardly out of the tubular standard to permit a handle 23 to be pivotally engaged thereon to facilitate rotation of the tubular standard 19 when it is desired to permit the tubular standard to have sliding engagement with the lower or main supporting bracket. Projecting from the lower portion 75 of the tubular standard 19 is a radially directed pin or projection 24 which is adapted to be passed upwardly through the slot 5 of the lower bracket arm 4 and is adapted to seat on said lower bracket arm 4 when the tubular standard 19 is rotated into the position illustrated in Figure 4. When the pin 80 24 is positioned above the stop arm 4 of the lower bracket as illustrated in Figure 4 the tubular standard is held in a predetermined elevated position with respect to the supporting bracket. The lower bracket arm 4 is also provided with a recess or groove at 85 85 for the reception of the stop pin 24 when the tubular standard 19 is rotated in the opposite direction to hold the tubular standard in another set position of adjustment as hereinafter more fully described.

90 The reinforcing rod 18 projects upwardly above the guide arm device 15 and is bent outwardly at substantially right angles to form a horizontal arm 26 which is curved at 95 27 and provides an extension 28 which projects substantially parallel to the window frame when the curtain support is in position for use. The upper portion of the reinforcing rod 18 projects through a tubular shank or 100 105 110 115 120 125 130

an extension tube 29 of the supporting standard. The upper portion of the tubular extension of the standard is bent outwardly at substantially right angles and then is curved and covers the bent portion of the reinforcing rod 27 to afford a portion 30 of a substantially U-shaped valance or drapery support comprising the tubular portion or rod 30 and a tubular section or rod 31 into which the end 28 of the reinforcing rod 18 projects as clearly illustrated in Figure 3. The drapery rod section 31 is slidably engaged on the extension or reinforcing rod 28 to afford a telescoping arrangement whereby the drapery rod may be extended to fit different sizes of window casings. The two sections forming the drapery rod are adapted to be rigidly connected by means of a clamping ring or collar 32 which is engaged over a tapered and slotted end of the drapery rod section 31 to permit said slotted end to be tightly clamped on the rod 28 in a predetermined position to provide a drapery rod of a desired length.

Engaged in the end of the drapery rod section 31 is a plug 33 a portion of which projects out of the end of the rod section 31 and is peripherally grooved to afford a neck portion 34 and a rounded or tapered head 35 to form a latch bolt which is adapted to be removably seated in a notched angle bracket 36 which is secured by means of screws or other suitable means to the upper portion of the window frame or casing opposite the side on which the supporting brackets 2 and 9 are secured.

The parallel arms forming part of the drapery rod or support are provided with notches or openings at 37 and 38 respectively, for the reception of the gudgeons 39 and 40 respectively of a curtain supporting hollow rod 41 which is adapted to be removably engaged on the drapery supporting rod and parallel to the longer telescoping portion thereof as clearly illustrated in Figure 3. The removable curtain supporting rod 41 has a plug 42 rigidly secured in one end thereof of which the gudgeon or pin 40 forms an integral part and projects beyond the end of the curtain rod as clearly illustrated in Figure 3. The gudgeon 39 forms a part of a slidable plug 43 which is slidably engaged in the opposite end of the hollow curtain rod 41 and is held in a projected position by means of a coiled spring 44 engaged within one end of the curtain rod 41. The inner end of the coil spring 44 seats against a stop plug 45 secured in the curtain rod 41.

The operation is as follows:

Drapery or a valance may be hung on the drapery rod 30-31 by removing the curtain rod or pole 41, and curtains may be hung on the curtain rod 41 which may be removably engaged in the arms of the drapery bracket as illustrated in Figure 3. Assuming that draperies and curtains are hung on the re-

spective drapery and curtain rods and that the improved curtain support is mounted on the window frame and in the full line position illustrated in Figure 1 of the drawings the first step necessary for the removal or the replacement of the draperies and curtains is to engage the handle 23 and slide the supporting standards 19-29 upwardly a short distance thereby causing the drapery rod 30-31 and the curtain rod 41 to be moved into the dotted line position A (Figure 1) thereby releasing the latch bolt 33-35 from the notched supporting bracket 36. The handle 23 is now swung about its pivot to a position at substantially right angles to the lower end of the standard 19 and said handle is swung through an arc causing the standard 19-29 to be rotated through a desired arc to swing the latch pin 24 into the plane of the slot 5 in the lower arm 4 of the base bracket. This arc of rotation of the supporting standard causes the drapery and curtain supporting rods to swing outwardly away from the window frame permitting the same to be slidably lowered into the dotted line position B of Figure 1 since the latch pin 24 is permitted to slide downwardly through the notch or slot 5 of the base bracket. The drapery and curtain supporting rods may be lowered to a convenient elevation or height whereby a housewife or any other person may conveniently remove the curtains and draperies from the supporting rods on which they are engaged. When the supporting standard 19-29 is slidably lowered through the arms of the base bracket the guide arm is gradually lowered with the notched plates 15 thereof slidably movable downwardly on the extension or guide bracket 9. When the guide arm reaches the upper flange or arm 6 of the base bracket the limit of downward movement of the drapery and curtain supporting rods is reached so that a person operating the improved curtain support may release the handle 23 and then remove draperies or curtains from the supporting rods or mount new or clean draperies and curtains in place as the case may be.

When the supporting standard 19-29 is slidably moved upwardly or downwardly the lower portion of the standard is permitted to have a smooth sliding movement through the fibre gasket 7 while the notched plates 15 of the guide arm are adapted to slide on the auxiliary guide bracket 9 which is braced or reinforced at spaced intervals by the spacing sleeves 14. The provision of the fibre gasket 7 and the brace sleeves 14 for the stationary bracket 9 eliminates the irregular and jerky movements of the slidable standard which ordinarily accompanies operation of slidable standards in earlier types of slideable curtain supports and the like. The provision of the brace sleeves 14 holds the auxil-

ary guide bracket 9 in a substantially rigid position so that the guide arm 15 may easily slide downwardly or upwardly thereon with substantially no noise or jerky movement and substantially the provision of the fibre gasket 7 in the upper arm or flange 6 of the base bracket insures a noiseless and even sliding movement of the lower portion of the supporting standard 19-29 downwardly or upwardly through the base bracket arms.

After the clean draperies and curtains have been mounted on the drapery and curtain supporting rods 30-31 and 41 the slideable supporting standard 19-29 may be slideably pushed upwardly back toward the elevated position A of the drapery and curtain supporting rods at which time the handle may again be swung at right angles to permit the supporting standard 19-29 to be rotated to swing the drapery and curtain supporting rods inwardly toward the window casing. The entire device may now be lowered from the dotted line position A of Figure 1 into the full line position thereby permitting the neck 34 of the latch bolt 33 to spring into the notched bracket 36 to hold the curtain support in its proper set position. With the pin 24 moved into the full line position as illustrated in Figure 4 supported upon the lower flange or arm 4 of the base bracket to assist in holding the lower portion of the curtain support in its set position.

When it is desired to have clear access to the windows to permit cleaning of the same or for any other reason the supporting standard 19-29 may be slightly raised to move the latch bolt 33 out of engagement with the supporting bracket 36 after which the handle 23 may be swung into a position at right angles to the lower end of the supporting bracket to permit the supporting standard to be rotated to swing the drapery and curtain supporting rods 30-31 and 41 from the elevated position A through an arc of substantially 180° outwardly away from the window frame into a position slightly above position C (Figure 1). The supporting standard may now be lowered to lower the drapery and curtain supporting rods into position C of Figure 1 thereby causing the pin 24 to seat in the groove or notch 25 (Figure 4) to hold the entire curtain supporting device in a set, out of the way position, affording clear access to the windows and to the window frame. The pocket afforded by the groove 25 for the reception of the latch pin 24 serves to act as a latching means for holding the curtain support in its out of the way position so that the same cannot accidentally swing back into position in front of the window frame.

It will of course be understood that numerous details of construction may be varied through a wide range without departing

from the principles of this invention, and it is therefore not purposed limiting the patent granted hereon otherwise than necessitated by the scope of the appended claims.

I claim as my invention:

1. A curtain support comprising an apertured base bracket adapted to be rigidly secured to a window frame, an auxiliary guide bracket interfitting said base bracket and also rigidly secured to the window frame above said base bracket, a standard slidably engaged through said base bracket and adapted to be rotated with respect thereto, a guide arm rotatably mounted on said standard and having slideable engagement with said guide bracket, a drapery supporting rod formed on the upper end of said standard, a curtain supporting rod removably supported on said drapery rod, and a notched supporting bracket adapted to be secured to the window frame to removably receive one end of the drapery supporting rod to assist in supporting the same in position across the upper portion of the window frame.

2. A window curtain support comprising a base bracket adapted to be rigidly secured on a window frame, a guide bracket interfitting the base bracket and also adapted to be rigidly secured to the window frame, a plurality of brace members connecting said guide bracket to the window frame to brace the guide bracket at spaced intervals, a supporting standard rotatably and slidably engaged through said base bracket, means on said base bracket through which said supporting standard projects to insure a smooth operation of the supporting standard, a guide arm rotatably mounted on said supporting standard and having sliding engagement with said guide bracket, a notched bracket adapted to be secured to the window frame, and drapery and curtain supporting rods supported on the upper end of said supporting standard adapted to be removably engaged with said notched bracket to hold the device in position upon a window frame.

3. A curtain support comprising a standard, a base bracket slidably and rotatably supporting said standard at one side of a window frame, a guide bracket interfitting said base bracket and also secured to the same side of the window frame, a plurality of means connected with said guide bracket at spaced intervals to reinforce the same, a notched bracket adapted to be rigidly secured on the opposite side of the upper portion of the window frame, a guide arm rotatably engaged on said standard and having sliding engagement with said guide bracket, gasket means carried by said base bracket and surrounding said standard to facilitate even operation thereof, and curtain supporting members mounted on the upper end of said standard and extending across the window frame to removably engage in said notched bracket.

4. A curtain support of the class described comprising a standard, a base bracket adapted to be rigidly secured to one side of a window frame and carrying gasket means 5 through which said standard slidably and rotatably projects, a guide bracket supported on said base bracket and rigidly secured to the window frame, spacer members disposed between said guide bracket and the 10 window frame, retaining means projecting through said guide bracket and through said spacer members to reinforce the guide bracket at spaced intervals, a movable guide member rotatably engaged on said standard and having 15 sliding engagement with said guide bracket, a notched bracket adapted to be secured on the opposite side of the window frame near the upper corner thereof, a U-shaped drapery rod rigidly secured on the 20 upper end of said standard and having a pair of oppositely positioned openings therein, a latch member in one end of said drapery rod adapted to be removably engaged in said notched bracket to hold the drapery rod supported 25 in position across the upper portion of the window frame, a curtain supporting rod, a gudgeon rigidly secured in one end thereof adapted to be removably projected into one of the openings in said drapery rod, and 30 a spring impelled gudgeon in the opposite end of said curtain rod adapted to be removably engaged in the opposite aperture of said drapery rod to hold the curtain rod removably supported in position.
- 35 5. A curtain supporting device of the class described comprising a base bracket adapted to be rigidly secured on one side of a window frame, a guide bracket having one end thereof supported on the base bracket and 40 the other end secured to the window frame, a plurality of means for bracing the guide bracket at spaced intervals, gasket means carried by said base bracket, a standard slidably and rotatably projecting through said 45 base bracket and through the gasket means thereon, an operating handle pivotally engaged on the lower end of said standard, a movable guide member rotatably supported on said standard and having sliding engagement with said guide bracket, a notched bracket adapted to be rigidly secured on the 50 opposite side of the window frame, and drapery and curtain supporting rods carried on the upper end of said standard and adapted to be removably engaged in said notched bracket.
- 55 6. A curtain support of the class described comprising a notched apertured base bracket adapted to be rigidly secured on one side of a window frame, a guide bracket interfitting said base bracket and having one end thereof secured to the same side of the window frame, a plurality of spacer means connected with said guide bracket to brace the 60 same at spaced intervals, a standard rotat- ably and slidably engaged through said base bracket, a handle pivotally engaged thereon, a guide arm rotatably engaged on said standard and having sliding engagement with said guide bracket, an auxiliary bracket adapted to be rigidly secured on the opposite side of the upper portion of the window frame, gasket means carried by said base bracket and surrounding said standard to insure even 65 operation thereof, a drapery rod rigidly secured on the upper end of said standard and adapted to project across the window frame to be removably engaged in said auxiliary bracket, a curtain rod removably supported by said drapery rod, and a pin projecting 70 radially from said standard for coaction with said base bracket to hold the standard and the drapery rod and the curtain rod in a predetermined vertical position of adjustment when the drapery and curtain rods are 75 swung outwardly away from the window frame.
- 80 7. A curtain support of the class described comprising a base bracket, a combination drapery and curtain supporting device rotatably and slidably engaged with said base bracket, a guide bracket interfitting said base bracket, and a guide member pivotally mounted on said combination drapery and curtain supporting device and having sliding engagement with said guide bracket.
- 85 8. A curtain support of the class described comprising a base bracket, a guide bracket interfitting the same, a standard rotatably and slidably engaged in said base bracket, a guide member rotatably engaged on said standard and having sliding engagement with said guide bracket, and drapery and curtain supporting members mounted on the upper end of said standard.
- 90 9. A curtain support of the class described comprising a base bracket, gasket means supported thereon, a standard slidably and rotatably engaged on said base bracket and projecting through said gasket means, a guide bracket interfitting said base bracket, means for bracing said guide bracket at spaced intervals, a guide member rotatably supported on said standard and having sliding engagement with said guide bracket, an auxiliary bracket, and drapery and curtain supporting members carried on the upper end of said standard for removable engagement with said auxiliary bracket when the curtain support is mounted on a window frame.
- 100 10. A curtain support of the class described comprising a pair of interfitting brackets adapted to be rigidly secured to one side of a window frame, spacer means for reinforcing one of said brackets at spaced intervals, a standard having rotatable and sliding engagement with the other of said brackets, a movable guide rotatably engaged on said standard and having sliding engagement with one of said brackets, a drapery support- 105
- 110
- 115
- 120
- 125
- 130

ing member rigidly secured on the upper end of said standard, a curtain supporting member removably engaged on said drapery supporting member, an auxiliary bracket adapted to be secured on the opposite side of the upper portion of the window frame, means carried by the drapery supporting member adapted to be removably engaged in said auxiliary bracket, and fibre means carried by 10 the bracket with which said standard is engaged, said fibre means serving to insure a smooth even operation of said standard with respect to said bracket.

11. A device of the class described comprising a vertical longitudinally movable member, horizontal members secured to the upper end thereof and adapted to support draperies and curtains, fixed and vertically movable guiding means for said member, 20 means for holding the vertical longitudinally movable member in adjusted position longitudinally, a fixed guide device interfitting said fixed guide means and slidably engaged by said movable guide means, and members for reinforcing the fixed guide device at spaced intervals.

12. A device of the class described comprising a supporting bracket, a vertical member slidably and rotatably engaged on said bracket, horizontal members secured to the upper end of said vertical member and adapted to support curtains, a guide bracket connected with said supporting bracket, means carried by said supporting bracket and by 35 said guide bracket to insure a smooth operation of said vertical member, and means for guiding the upper end of the vertical member in any vertical position with said means having sliding engagement with said guide bracket.

40 13. In a device of the class described the combination with a pair of interfitting fixed brackets adapted to be secured on a window frame, of a curtain supporting member slidably and rotatably supported on said brackets, and means connected with said interfitting brackets adapted to insure a smooth even operation of the curtain supporting means.

14. In a curtain supporting device of the 50 class described the combination with a pair of interfitting brackets adapted to be secured to a window frame, of a curtain supporting member rotatably and slidably engaged on one of said brackets, a guide member on said curtain supporting means having sliding engagement with the other of said brackets, and means connected with said interfitting brackets to insure a smooth and even operation of the curtain supporting member.

60 In testimony whereof I have hereunto subscribed my name at Chicago, Cook County, Illinois.

SIMEON L. SAWYER.
